UNITED STATES PATENT OFFICE.

EMIL GATHMANN, OF BALTIMORE, MARYLAND.

APPARATUS FOR TEEMING MOLDS.

1,321,300.

Specification of Letters Patent. Patented Nov. 11, 1919.

Application filed June 28, 1919. Serial No. 307,311.

To all whom it may concern:

Be it known that I, EMIL GATHMANN, a citizen of the United States, residing in Baltimore city, State of Maryland, have invented certain new and useful Improvements in Apparatus for Teeming Molds, of which the following is a specification.

This invention relates to apparatus for teeming molten metal from ladles and particularly to ladles or containers for teeming metal ingots, although the invention is not confined to this class of apparatus, and could be used for teeming castings or any other molten product where refractory containers must be employed due to high temperature of the molten metal.

In ordinary practice the ladle or container for the molten metal is provided at the bottom or in its lower portion with a discharge orifice or nozzle, which is controlled by what is termed a stopper, the lower portion of which is adapted to enter a seat at the entrance of the discharge orifice. This entering portion is connected with a metallic rod surrounded by sleeves of refractory material and passes up through the molten metal and the slag blanket in the container or ladle. The diameter of the refractory sleeves covering the stopper rod is substantially the same as that portion of the stopper which enters the discharge orifice or sealing seat of the nozzle, although the stopper portion itself is usually tapered or rounded.

It occasionally happens that in using this type of stopper a vortex is formed in the molten metal which sweeps non-metallic particles that are carried in greater abundance in the upper portions of the liquid metal than in the lower portions thereof, due to their difference in specific gravity, downward to the discharge orifice and into the article being cast. Particles of slag held in suspension mostly in the upper portion of the molten metal, although ordinarily tending to rise to the top thereof, due to their specific gravity, also frequently pass downward in a stratified vertical stream or streams, and reach the discharge opening or nozzle and are discharged into the casting or ingot being formed. It is most desirable to prevent, or to reduce as much as possible, the passage of included slag and non-metallic

material with the metal being teemed, as these non-metallic impurities and slag particles all tend to lessen the homogeneity of the article cast.

According to my invention I provide a device of very simple character which greatly remedies this difficulty in teeming from ladles of the kind referred to, in that it prevents direct, stratified, downward, vertical currents through the mass of metal to the discharge opening or nozzle, and also prevents to a great degree vortexing of the metal about the discharge opening, which vortexing in itself produces downward, vertical, stratified currents which it is desirable to reduce or obviate.

I have discovered by a series of experiments that if a suitable baffling device be applied near the discharge opening, preferably attached to the stopper near that portion which controls the discharge opening, the flow of metal through the discharge orifice will be made more uniform and not stratified, and I believe this to be a broad feature of improvement in this class of ladles. More specifically the invention consists in providing a stopper or stopper rod, or rather the stopper sleeve, with an enlarged portion near the entering end of the stopper, which baffling device is of materially larger diameter, at least two to three times, than either the stopper itself or the refractory sleeves surrounding the stopper rod, and at least four to eight times the diameter of the discharge outlet or nozzle. This baffle plate or device has the effect of preventing the metal from flowing directly downward or vertically adjacent to the stopper rod in a segregated stream or streamlets to the discharge orifice or nozzle, and promotes a more uniform, greatly-to-be-desired, downward settling of the molten charge as a whole in the ladle or container, and induces an entrance into the discharge orifice or nozzle from an approximately horizontal rather than from a direct vertical strata of the metal. In this way vortexing is largely prevented, and the greatly-desired more homogeneous lower strata of the molten metal is progressively delivered to the ingot or casting being teemed, which lower strata as before stated is freer of included, non-

metallic particles, and also suspended slag, due to the difference in specific gravity of these impurities and the molten metal, than the upper portion of the metal carried by the ladle.

My improvements are illustrated in the accompanying drawings and will be herein-after more specifically described.

In the drawings:—

10 Figure 1 is a view, mainly in section, illustrating a ladle for teeming ingot molds, embodying my improvements and showing in perspective a mold associated with said ladle so as to receive metal therefrom. In this 15 particular instance I have illustrated what is known in the art as a plate or slab mold, the nozzle of the ladle being specially constructed to teem this kind of a mold.

20 Fig. 2 is a detail view, on an enlarged scale and in section, showing the preferred way of equipping a ladle stopper, rod, or sleeve with my improvements.

The ladle A is in general of well-known construction, comprising a casing a, a lining 25 b of suitable refractory material and straps c which strengthen the structure. In this instance the ladle discharges through an orifice in the bottom of the ladle preferably located centrally. The discharge orifice X 30 is located in a bushing or plug C of suitable refractory material. The inner or upper portion of the orifice is preferably tapered as shown, and as is usual. The discharge nozzle is constructed in accordance with the 35 principles set forth in my patents of March, 25, 1919, Nos. 1,298,034, 1,298,035 and 1,298,036, but in the present case the nozzle is constructed to teem plate or slab molds of the kind illustrated in Fig. 1. The details 40 of construction of the nozzle are not important so far as my present invention is concerned, but preferably the nozzle is constructed as illustrated. The bushing or 45 plug C is held in place by a plate D bolted to the bottom of the ladle as illustrated or otherwise suitably secured thereto. E, E' indicate blocks of refractory material having vertically arranged orifices e. Two such 50 blocks are preferably employed and the orifices e communicate with horizontal passages F which in turn communicate with a horizontally arranged passage g in a centrally arranged block G. The blocks E, F 55 and G are held in a casing or frame H, in the manner indicated. The central portion h of the frame supports the central block as well as the blocks E and F, while the casing H is provided with a flange h' which 60 supports the outer ends of the blocks E and F. Sand, clay or other suitable material surrounds the blocks as indicated and these blocks are also preferably covered with such insulating material, after which a plate I 65 may be placed over all and secured in place

if desirable. The frame H is provided with arms or extensions J which are connected with bolts K attached to the ladle. In this way the discharge nozzle is held firmly in place but may be detached when required. 70

The mold V, shown in Fig. 1, is of well known construction. It rests on a stool V' in the usual way.

It will be observed that the nozzle discharges approximately vertically into the 75 mold and preferably, as specified in my before-mentioned patents, the discharge openings of the nozzle are of larger diameter collectively than the discharge orifice of the ladle and care is taken that the streams of 80 metal issuing from the nozzle are directed away from the side walls of the mold. I wish to have it clearly understood, however, that my present invention does not relate to the special construction of the 85 nozzle. It may be applied to ladles equipped with various kinds of nozzles, either those shown in my patents before mentioned, or others used or known in this 90 art. My present invention relates to devices for controlling the discharge of metal from the ladle.

As hereinbefore stated, I have found in the old, actual practice that the discharge 95 of metal from the ladle is frequently irregular, and I have accounted for this irregularity by the fact that vortexes have been observed in the molten metal in the ladle or container, which I find are caused by the direct, downward, stratified flow to the discharge nozzle. I have also observed that at times slag is drawn down from the lower part of the blanket of slag covering the meal, and frequently some slag particles held in suspension pass down through relatively cleaner molten metal in segregations, and are discharged from the nozzle with the metal. This accounts for irregularities in the homogeneous quality of metal delivered 100 from the container or ladle. I have discovered that these difficulties and objections may be overcome by providing devices, which will largely prevent or reduce vortexing of the metal, or prevent downward passage 105 of stratified streams or currents occurring in the material as the metal is discharged from the nozzle, and that will direct the flow of the stream or current in a horizontal plane or course toward the discharge orifice, allowing the upper mass of metal to become more uniform and free from air, slag and non-metallic particles before its discharge from the ladle through the nozzle, as normally will occur by the action 110 of the laws of gravitation.

In its simplest form my invention consists in providing a baffling device which is associated with that part of the stopper or rod sleeves which controls the outlet from the 115

ladle. This baffling device preferably consists of a plate or part of much larger diameter than either the stopper proper or the stopper rod refractory sleeves which has 5 the effect of preventing vertical downward stratified currents or streams of metal carrying impurities from the higher and more segregated area of the metal in the ladle or container, and insures the more quiet and 10 uniform passage of metal laterally toward the discharge orifice before entering the same, thus preventing any stratified or segregated downward current or stream. Where such a device is employed it should 15 be so arranged on the stopper, stopper rod or rod sleeves that it shall not touch the ladle lining either at side or bottom when the stopper plug *per se* closes the orifice or discharge nozzle, as it might otherwise add 20 here thereto by freezing of molten metal at this part of ladle and thus interfere with the proper operation of the stopper and discharge nozzle. As shown, the baffling device S on stopper Z which must usually be 25 opened and closed many times during the teeming of a heat of metal is preferably made circular in cross section, and preferably has a tapered top as shown. It has a central opening through which extends the stopper 30 proper Z which is made of refractory material, as is the baffle plate, and is attached to the end of the stopper rod W. The sleeves T of refractory material are shown of ordinary construction. Other shapes or cross 35 sections of baffling devices can obviously be used as may be found of value in specific ladle construction without departing from the spirit of my invention.

The stopper proper is preferably of such 40 vertical length below the baffle that when the stopper enters its seat, the bottom of the baffle is held away from the bottom wall of the ladle. Preferably the bottom of the baffle is flat and horizontal, while the top 45 thereof is preferably tapered as shown.

In operating the stopper, the best results can be obtained if it is not raised in the ladle any more than sufficient to allow the molten metal to flow with sufficient freedom 50 through the discharge opening.

I claim as my invention:—

1. A ladle or container for molten metal provided with a discharge orifice having a valve seat and provided also with a stopper 55 rod having a valve portion which closes said discharge orifice, and a baffling device mounted on said stopper rod immediately above that portion which closes said orifice and which is materially larger in diameter 60 than the valve seat, whereby direct vertical stratified currents through the metal carried in the ladle are prevented.

2. A ladle or container for molten metal provided with a discharge orifice having a 65 valve seat and provided also with a stopper

rod having a valve portion adapted to close said orifice, and a baffling device associated with said stopper rod of materially larger diameter than said stopper rod and also of materially larger diameter than the valve 70 seat.

3. A ladle or container for molten metal provided with a discharge orifice having a valve seat, and a stopper comprising a rod and having a portion fitting said valve seat 75 and adapted to close said orifice, and a baffle larger in diameter than the upper portion of the valve seat and the lower portion of which, when the orifice is closed by the stopper, is held above the lower wall of 80 the ladle, the vertical length of the stopper below said baffle being greater than the depth of the stopper seat.

4. A ladle or container for molten metal provided with a discharge orifice having a 85 valve seat at its upper portion and provided also with a stopper rod having a valve portion adapted to close the discharge orifice at said valve seat and a baffling device for preventing direct vertical stratified currents 90 through the molten metal carried in the ladle mounted above said valve portion on the stopper rod, said baffling device being out of the zone of contact with the valve 95 seat.

5. A ladle or container for molten metal provided with a discharge orifice having a valve seat, and provided also with a stopper constructed of refractory material having a portion which controls said orifice adapted 100 to seat in said valve seat and associated with an enlarged baffling device separably connected with the stopper rod, which baffling device is out of contact with the ladle lining and the valve seat of the orifice when the 105 stopper closes said orifice.

6. A ladle or container for molten metal provided with a discharge orifice having a valve seat, and means for closing said orifice comprising a stopper rod inclosed in refractory material and a stopper valve adapted to seat in said valve seat, and a baffling device of materially larger diameter than the stopper rod and its inclosing sleeve of insulating material and which is arranged near 110 the end of the stopper rod which controls the discharge orifice and is out of contact with the valve seat of said orifice both when the orifice is closed and open.

7. A ladle or container for molten metal 115 provided with a discharge orifice in its bottom portion, a valve seat at the upper portion of said discharge orifice, a stopper for controlling said discharge orifice and means in the ladle above said discharge orifice of 120 materially larger diameter than the stopper rod and the valve seat of said orifice for preventing downward, stratified currents through the molten metal to the discharge opening or nozzle of the ladle. 125

8. A ladle or container for molten metal provided with a discharge orifice, having a stopper seat and a stopper, and a baffle of relatively large diameter as compared with 5 said stopper seat and stopper, and the lower side of which when the stopper is seated in the stopper seat is held above the said stop-

per seat and the lower walls of the ladle, the vertical length of the stopper below said baffle being greater than the depth of stop- 10 per seat.

In testimony whereof, I have hereunto subscribed my name.

EMIL GATHMANN.
